UNITED STATES PATENT OFFICE

ADOLF V. SCHARWENKA, OF NEW YORK, N. Y.

RAILWAY-SWITCH.

1,109,943.

Specification of Letters Patent. Patented Sept. 8, 1914.

Application filed June 10, 1914. Serial No. 844,130.

To all whom it may concern:

Be it known that I, ADOLF V. SCHARWENKA, a citizen of the United States, residing in the city of New York, borough of Manhattan, in the county and State of New York, have invented a certain new and useful Improvement in Railway-Switches, of which the following is a specification.

The invention relates to the operation of movable-frog double slip switches, and the main object of the invention is to provide means for throwing the frog-points and end-points from a single stand by the single movement of a lever.

Another important object is to provide a positive automatic locking means for holding the switch-operating mechanism and the switch-points reliably in the several positions to which they are thrown.

A further object is to provide a switch-stand of simple inexpensive construction in which the mechanism is inclosed and protected, and which may be located below the level of the top of the rail, thus permitting installation in electrified yards.

Another object is to provide an inexpensive and easily replaced portion adapted to be broken and relieve the strains without serious damage to the mechanism when the frog-points are accidentally run through by a locomotive or car.

The invention consists in certain novel features of construction and arrangement by which the above objects are attained, to be hereinafter described and claimed.

The accompanying drawings form a part of this specification, and show an approved form of the invention.

Figures 1, 2 and 3 are diagrammatic plan views on a small scale, indicating the arrangement and positions of the movable points, with the operating lever, in the three conditions of two straight movements and the double-slip movement. Fig. 4 is a plan view on a larger scale, showing the switch-stand with the cover removed. Fig. 5 is an end elevation of the same, showing the location of the stand relatively to an adjacent rail. Fig. 6 is a corresponding side view.

Fig. 7 is a vertical section partly in elevation, the plane of section being indicated by the line 7—7 in Fig. 4. Figs. 8, 9, 10 and 11, are vertical sections, partly in elevation, taken on the lines 8—8, 9—9, 10—10, and 11—11, in Fig. 4. Fig. 12 is a similar view showing a portion of the lock-

ing device. Fig. 13 is a corresponding view showing the breakable bearing for the shaft. Fig. 14, is a vertical section on a larger scale, corresponding to Fig. 7 but showing the parts in transition from one position to another. Fig. 15 is a cross-section through the switch-operating shaft, showing a portion of the lever in elevation.

Similar letters of reference indicate the same parts in all the figures.

The switch-stand comprises a shallow rectangular box or receptacle A cast with a base plate or flange A¹ by which it may be securely fastened to the ties or other support, and having a cover A² protecting the mechanism contained in the stand. It may be located near the track and its vertical height and that of the contained mechanism is so little as to permit its installation at or below the level of the rail-tread if desired. Extending through the box is a horizontal shaft B supported in suitable bearings therein, and projecting at one end to receive a split lever B¹ B² by which the shaft may be turned through an arc of approximately 200°, or a little more than a complete half turn. At a right angle to the shaft, and below the latter, are two bars or slides C C¹ projecting through the opposite side-walls of the box and shaped at the ends to be coupled to the connecting-rods M, M¹, M² by which the points are thrown, as will be described. A portion near the midlength of each is toothed to form a rack C² C³ adapted to be engaged by the teeth of segmental pinions D and D¹ each mounted on the shaft above its slide.

On the inner margin of each slide is an enlargement or wing, D² D³, each having two separated V-shaped notches or cavities marked d d¹, and d² d³ respectively, and E, E¹ are vertically swinging dogs mounted on pivots e e¹ beneath the shaft B, and each shaped on its under face to engage either of the pair of cavities presented by the end-wise movement of its slide and hold the latter at each extreme of such movement.

The shaft B carries two circular disks or cams E² E³ located above the dogs and each adapted to engage peripherally the upper face of its dog and hold it in engagement with its cavity until released by the presentation of an omitted or cut-away portion of the cam, as at E⁴ E⁵, which permits the dog to lift by the action of the inclined side of the cavity against the correspondingly in-

clined side of the dog when its slide is moved longitudinally.

- F is a disk mounted on the shaft B, having three notches f , f^1 , f^2 in its periphery adapted to be engaged by a locking-lever F^1 pivotally mounted on the plate A^1 within the box, and weighted as at F^2 to insure automatic engagement with the notch presented and thus hold the shaft. The lever F^1 is released by the lifting action of the toe G^1 of a foot-lever G extending through an opening in the end of the box, pivotally mounted on the plate A^1 and operated by pressure on a foot-plate G^2 forming the short arm of the foot-lever. The toe G^1 lies beneath the weighted arm of the locking-lever and lifts the latter when foot-plate is pressed downwardly by the switchman prior to changing the position of the switch.
- 20 The hand-lever B^1 B^2 by which the shaft is partially rotated is in two portions each having a boss, B^3 B^4 , loosely encircling the overhung end of the shaft B and notched radially as at b b^1 to receive a lug B^5 set radially in the shaft; each notch is long enough to afford a carefully determined amount of lost motion, and the opposed engaging faces b^2 , b^3 , of the notches presented toward the lug are so placed as to grip the latter between them when both arms of the lever are extended side by side, as shown in Figs. 1 and 4, and by grasping both arms as one and swinging both to the position indicated in Fig. 3, or completely over, the shaft B is turned to the other extreme of its arc of 200° , and by separating the arms and allowing them to lie in opposite directions as in Fig. 2, the lost motion due to the length of the notches causes the shaft to be turned through a portion of its arc to an intermediate position. The arms of the lever are weighted to insure descent and the full operation of the mechanism in any of the three positions.
- 45 The full lines in Fig. 4 to 13 inclusive, show the shaft and its connections in the normal or first straight condition of the switches and frog-points as indicated in Fig. 1. The dogs E E^1 are engaged with the cavities d d^2 of the slides and are held therein by the circular portions of the cams E^2 E^3 , and the locking-lever F^1 is engaged in the notch f of the disk F. The slides are both at the extreme left end of their throw, and through the connecting-rods M, M^1 and M^2 and T-levers N, N^1 and N^2 the end-points L L^1 , L^2 L^3 and O O^1 , O^2 O^3 , with the frog-points R R^1 and S S^1 are held in position to allow the passage of trains diagonally across 60 as indicated by the arrows in Fig. 1.
- By grasping the inner arm B^1 of the switch-lever alone and throwing it completely over, or by raising both arms to the vertical and allowing them to separate and fall by gravity, one on each side, and at the

same time pressing upon the foot-plate G^2 to release the locking-lever F^1 from the disk F, the shaft is partially rotated to a position at which the cut-away portion of the cam E^2 is presented above the dog E, and the teeth of the pinion D engage the rack C^2 and throw the slide C to the full extent in the opposite direction, which through the connecting-rod M and T-lever N, moves the frog-points R R^1 and S S^1 to the positions shown in Fig. 2 without changing the positions of the end-points, in which trains may run along the other diagonal course, as indicated by the arrows in such figure. In this position the dog E is now engaged in the notch d^1 , and the cam E^2 advanced sufficiently to hold it reliably, and the notch f^1 of the disk F is engaged by the locking-lever F^1 . During this operation the other slide C^1 has remained stationary but the teeth of the pinion D^1 have advanced ready to engage its rack, and the cam E^3 sufficiently to be about ready to release the dog E^1 on a further movement in the same direction.

By grasping the lever arm B^2 and throwing it completely over alongside its mate B^1 , the dog E^1 is released by the cut-away portion of the cam E^3 , the rack C^3 is engaged by the teeth of the pinion D^1 , and the slide C^1 thus thrown to its extreme opposite position, and through its connecting-rods M^1 M^2 , moves the end-points L L^1 , L^2 L^3 and O O^1 , O^2 O^3 to the positions shown in Fig. 3, the frog-points remaining as before, in which position trains may travel in both directions over the curved ways of the slip, as indicated by the arrows. During this change the slide C and its connections remain stationary with its notch d^1 still engaged by the dog E and held by the circular portion of its cam E^2 while the teeth of the pinion D are advanced idly out of mesh with the rack C^2 .

The switch-points may be thrown from the first position, Fig. 1, to the third position, Fig. 3, by grasping both arms of the lever and throwing them both completely over, and the switches can be thrown directly to any of the three positions from any other position, and automatically released and relocked. In all changes it is necessary first to depress the foot-plate G^2 and release the locking-lever F^1 .

The toothed segmental portions of the pinions D D^1 and the cut-away portions E^4 E^5 of the cams E^2 E^3 are of such lengths and so located angularly in advance one of the other, as to permit the above described movements of the slides, and engagement and disengagement automatically of the locking-dogs with the slides.

To avoid disarrangement of the apparatus by the accidental running through of the frog-points or other cause, the caps A^3 A^3 of the shaft bearings are made designedly weak

so as to permit them to break easily and allow the shaft and the cover A² to be lifted and relieve the parts from strain. The caps are inexpensive and may be easily and quickly replaced, thus greatly reducing the damage and inconvenience caused by this common form of accident.

It will be noted that the connecting-rods M¹ M² extend from both ends of the slide C¹, while only one end of the slide C is thus connected, making the required three points of connection and leaving one end of the slide C free; this arrangement permits the stand to be reversed and connected as may be found necessary or desirable for convenience of location and operation.

The switch-stand is low and the lever-arms in all three positions lie close to the ground, thus permitting the passage of contact-shoes of electric trains without interference, and the positions of the switches are plainly indicated by the positions of the arms relatively to each other and to the box, thus lessening the danger of misplacement. The automatic lock and release of the slides insures complete movement and correct positions.

I claim:—

1. In an apparatus of the character set forth, a shaft, segmental pinions thereon having the teeth of one in advance angularly of the other, a slide for each of said pinions, having racks adapted to be engaged with such teeth to move said slides, means for partially rotating said shaft, and a plurality of switch-points and connections to the latter from said slides.

2. In an apparatus of the character set forth, a shaft, segmental pinions thereon having the teeth of one in advance angularly of the other, a slide for each of said pinions, having racks adapted to be engaged with such teeth to move said slides, means for partially rotating said shaft, a plurality of switch-points and connections from the latter to said slides, and means actuated by the movement of said shaft for automatically locking and releasing said slides.

3. In an apparatus of the character set forth, a shaft, segmental pinions thereon having the teeth of one in advance angularly of the other, a slide for each of said pinions, having racks adapted to be engaged with such teeth to move said slides, means for partially rotating said shaft, a plurality of switch-points and connections to said switch-points from said slides, and a locking means for said shaft arranged to require manual operation to release said shaft prior to a movement of the latter.

4. In an apparatus of the character set forth, a shaft, a plurality of switch-points, means actuated by the partial rotation of said shaft for moving such points, a two-part lever loosely mounted on said shaft and

having its arms arranged to lie side by side to be thrown as one, or separated to be thrown separately, a lug on said shaft, and a notch in each of such arms, adapted to engage said lug and thereby partially rotate 70 said shaft.

5. In an apparatus of the character set forth, a shaft, segmental pinions thereon having the teeth of one in advance angularly of the other, a slide for each of said pinions, 75 having racks adapted to be engaged with such teeth to move said slides, movable dogs arranged to lock and release said slides, means for partially rotating said shaft, a plurality of switch-points, connections to 80 the latter from said slides, and means actuated by said shaft for automatically holding said dogs in engagement with said slides, and permitting their disengagement therefrom.

6. In an apparatus of the character set forth, a shaft, a longitudinally movable slide actuated by the partial rotation of said shaft, said slide having cavities therein, a vertically movable dog adapted to engage 90 said cavities and lock said slide, a cam on said shaft adapted to hold said dog in engagement, and to permit its disengagement, and connections from said slide to a switch-point.

7. In an apparatus of the character set forth, a shaft, segmental pinions thereon having the teeth of one in advance angularly of the other, a slide for each of said pinions, having racks adapted to be engaged with such teeth to move said slides transversely of said shaft, said slides having cavities therein, vertically swinging dogs arranged to engage said cavities, cams on said shaft having cut-away portions, and arranged with the cut-away portion of one in advance angularly of the other, said cams adapted to engage said dogs and hold them in engagement with such cavities, and to release said dogs by the presentation of such cut-away portions thereto, means for partially rotating said shaft, a plurality of switch-points, and connections to the latter from said slides.

8. In an apparatus of the character set forth, a box, a horizontally disposed shaft mounted therein, segmental pinions on said shaft, longitudinally movable slides beneath said shaft, having racks adapted to be engaged by the teeth of said pinions, means for locking said slides against movement, bearings for said shaft, and relatively fragile caps for said bearings, adapted to break under excessive strain and permit said shaft to rise in said bearings, a plurality of switch-points, and connections to the latter from said slides.

9. In an apparatus of the character set forth, a horizontally disposed shaft, a plurality of switch-points, means actuated by 130

the partial rotation of said shaft to three positions for correspondingly setting said points, a lug on said shaft, a two-part lever loosely mounted on said shaft and having two parallel arms, each of said arms having a notch adapted to engage said lug, said arms constructed and arranged to engage said lug and lie side by side approximately horizontally in one position of said shaft and points, to lie side by side and approximately horizontally in the opposite direction in a second position of said shaft and points, and to be separated and lie extended in opposite directions and approximately horizontally in the third position of said shaft and points.

10. In an apparatus of the character set forth, a shaft, segmental pinions thereon having the teeth of one in advance angularly of the other, a slide for each of said pinions, having racks adapted to be engaged with such teeth to move said slides

transversely of said shaft, said slides having V-shaped cavities therein, vertically swinging dogs arranged to engage such cavities automatically, cams on said shaft adapted to hold said dogs in engagement in said cavities and to release them from such engagement, a disk on said shaft having notches in its periphery, a locking-lever arranged to engage automatically with one of said notches presented to said locking-lever, means for partially rotating said shaft, manually operated means for disengaging said locking-lever from said disk, 30 and a plurality of switch-points and connections therefrom to said slides.

In testimony that I claim the invention above set forth I affix my signature, in presence of two witnesses.

ADOLF V. SCHARWENKA.
